UNITED STATES PATENT OFFICE.

FRANK H. BLACKMARR, OF CHICAGO, ILLINOIS.

DESIGN FOR A CIGARETTE-CASE.

54,979.

Specification for Design.

Patented Apr. 27, 1920.

Application filed October 22, 1917. Serial No. 197,969. Term of patent 14 years.

To all whom it may concern:

Be it known that I, FRANK H. BLACKMARR, a citizen of the United States, residing at Chicago, in the county of Cook and State of Illinois, have invented a new, original, and ornamental Design for Cigarette-Cases, of which the following is a specification, reference being had to the accompanying drawing, forming part thereof, and in which—

The figure is a perspective view of a cigarette case, showing my new design.

I claim:

The ornamental design for a cigarette case, as shown.

FRANK H. BLACKMARR.
